UNITED STATES PATENT OFFICE.

GEORGE W. WHITE, OF NEW YORK, N. Y., ASSIGNOR TO P. AND F. CORBIN,
OF NEW BRITAIN, CONNECTICUT.

DESIGN FOR FRONT AND STRIKE PLATES FOR LOCKS.

Specification forming part of Design No. 5,836, dated April 30, 1872.

To all whom it may concern:

Be it known that I, GEORGE W. WHITE, of the city, county, and State of New York, have invented or produced a new and original Design for the Front Plate and Strike-plate of Locks; and the following is declared to be a full and correct description thereof.

This design relates to an ornamental edge for the raised surface, forming the border for the front plate or for the strike-plate of a lock, and also to a similar ornamental edge for the border surrounding the openings in said plates.

In the drawing I have represented said design as upon the front plate of a lock.

The design for the edges aforesaid consists of a series of bud and leaf ornaments, sometimes called "knops" or "knospa." These are shown at *a* upon the inner edges of the raised

surface forming the border of the plate, and at *b c d e h* upon the outer edges of the raised surfaces surrounding openings in the plate.

At *c* the design is slightly varied, double-leaved ornaments without buds being shown; and at *f f* the edges are shown as straight, with V-notches therein.

I claim—

The design of the shape and configuration of the ornamental border of the front or strike plate, as described and shown.

Signed by me this 8th day of March, A. D. 1872.

GEO. W. WHITE.

Witnesses:

GEO. T. PINCKNEY,
CHAS. H. SMITH.
